APPARATUS FOR ORE CONCENTRATION

Rutherford B. Martin, Roselle, N. J., assignor,
by mesne assignments, to Tennessee Corpora-
tion

Application August 5, 1930, Serial No. 473,184

19 Claims. (Cl. 209—441)

This invention relates to improvements in the concentration of ores, and more particularly to improving apparatus for concentration by water gravity table methods.

5 Heretofore the separation of one mineral from another by gravity tables usually has been effected by the design and the angle of the riffles relative to the tilt of the table and the impact of the head motion. In some cases, arrangements 10 in which the deck is in two or more planes joined by sloping surfaces have been employed. In prior practice, the operation has been carried out with finely crushed ores in a freely flowing pulp. Dis- 15 advantages have been encountered, particularly in the small capacity a given table will handle.

One of the principal objects of this invention is to produce a greater concentrating capacity with gravity tables than heretofore accomplished.

20 Another object of this invention is to concentrate by gravity tables a coarser feed than heretofore employed.

Yet another object of this invention is to give 25 a greater mobility to the mineral and gangue particles in the flowing pulp undergoing concentration and thereby improve the stratifying action of the table with improvement in the grade of concentrate while at the same time increasing the capacity of the table.

30 A further object of this invention is to discharge from gravity tables the separated constituents of ores at a greater speed than heretofore possible.

In practicing my invention I utilize the well 35 known gravity concentrating tables such as the Wilfley, the Deister, the James and the like, which had been in common use for gravity separation of ores. I so modify the construction thereof as to render the action of said tables 40 vastly more efficient than heretofore. I place upon the tables wires or the equivalent, so as to facilitate the action of the table and the separation of the ore from the gangue. These wires are generally placed at an angle to the 45 riffles and usually I provide one or more sets of parallel wires placed apart a sufficient and satisfactory distance.

I have found that by covering the riffles of concentrating tables with metal strips, or more par- 50 ticularly, wires spaced $1\frac{1}{4}$ inches apart, the volume of feed may be increased ten to twenty times that a normal table would handle. It is im- 55 portant that the wires shall be inclined at an angle to the riffles such that the movement lengthwise of the table of the solid particles

(ore and/or sand) in the portions of the body of pulp on the table that tend to remain above the level of the riffles is retarded and at the same time such particles are guided laterally of the table. The angle of inclination of the wires 60 to the riffles may be varied through a wide range so long as the conditions above mentioned are satisfied. For best results the nature of the ore and the size of the feed particles should be considered in determining the angle at which 65 the cross wires should be set. However, I have obtained equally good results, in regard to grade of concentrate and impoverishment of tailings, when the wires were set at one angle, and then changed to the diametrically opposite direction, 70 the noticeable difference being in the increased capacity of the table.

In treating a non-metallic ore, having sub- 75 stantially the same specific gravity as the gangue, such as phosphate ores, when agglomerated into floccules with the capacity of sinking less rapidly in water than the gangue particles, (see my U. S. Letters Patent No. 1,797,356, dated March 24, 1931), I have obtained highly satisfactory re- 80 sults by placing a set of wires upon the riffles at about a 22.5° angle to the riffles so that the wires extend diagonally across the table from the end away from the point of feed and the head motion towards the point of feed and the head motion. This provision will hasten the 85 movement of concentrates across the table while retarding their movement lengthwise of the table. At the same time this makes it possible to accelerate the movement of the sands along the riffles by speeding up the rate of reciproca- 90 tion of the table.

A still further improvement in result has been 95 obtained by associating a set of cross wires, inclined at a 22.5° angle as above described, with a second set of cross wires inclined at a greater angle to the riffles, and preferably at substan- 100 tially right angles to the first set, the second set of cross wires being confined to the portion of the table adjacent the point of feed to the table. In this way the movement of the mate- 105 rial lengthwise of the table in the zone above the level of the main or primary riffles is still further retarded in the earlier stages of the treatment of the ore on the table when it is desirable to promote a high degree of stratifying action.

The cross wires should not be of such dimen- 110 sions or in such position as to disturb unduly the ore bed while the table is in motion, but nevertheless should be so disposed with respect to the ordinary or primary set of riffles as to be posi-

tioned within the body of material at least in the portions of the table adjacent the point of feed of pulp thereto. In practice it has been found most advantageous to employ wires of from 12 5 to 15 B. and S. gauge.

Wire screen of two inch mesh has been used, with inferior results, the junction of the wires forming the mesh unduly churning up and disturbing the stratification of the bed.

10 Riffles with a depth of two or more inches at the head motion end of the table and tapering to $\frac{1}{8}$ of an inch towards the far end of the table, fitted with cross wires, have been used with great success from the point of view of tonnage, such 15 construction facilitating the settling and movement of the sands under the cross wires to the discharge end of the table.

When treating a non-metallic ore, such as agglomerated phosphate, the cross wires impart 20 mobility to the mineral and gangue particles in the body of pulp on the concentrating bed. The flow of water at right angles to the riffles washes the phosphate across the table where it is recovered as concentrates while the sand (gangue) 25 particles settle between the riffles and are carried along in the channels between the riffles beneath the cross wires to the end of the table where they are discharged.

In the accompanying drawings constituting a 30 part hereof and in which like reference characters indicate like parts,

Figure 1 is a plan view diagrammatic in character showing in dotted lines the direction of wires placed on the table, and

35 Figure 2 is a similar view showing two sets of parallel wires on the table.

Figure 3 is a perspective view showing a table of the Wilfley type equipped with an arrangement of cross wires or cross riffles arranged generally as 40 shown in Figure 2.

Referring to Figure 1, I have indicated by the broken line 1 a series of wires parallel to each other and spaced a suitable distance apart at the 45 head end 4 of the table 5, containing a series of riffles 6 which have a maximum depth at the head end of the table and tapering down to a minimum depth at the opposite end thereof. The wires 1 are generally placed only at the head end of the table, but may extend over the major portion 50 thereof. I have found that the increase in efficiency is very small if wires are added at the discharge end of the table.

Instead of the wires 1, which are substantially 55 at right angles to the riffles, I may use wires 2 which are at an angle of about 45° to said riffles. The wires 2 are spaced apart and parallel over substantially the head end of the table, although they may extend over the entire table if desired.

60 Instead of the sets of wires 1 and 2, I may place a set of parallel wires 3 suitably spaced apart at an angle of about 22.5° to the riffles as shown. With this arrangement I have still further substantially increased the capacity of the table with- 65 out markedly lowering the grade of the concentrate.

In Figure 2 I have shown the use of two sets of wires 2 and 3 of which the wires 2 are in parallel 70 and at the head end of the table and the wires 3 extend from the furthermost wire 2 to the tails end of said table. The ore is fed at point 7, the tails are taken off at 8, the middlings at 9, and the concentrates at 10. This arrangement I have 75 found to be even more effective in increasing the

efficiency of the table than any of those described above. The wires may be secured to the table in any suitable manner as by tacking them upon the riffles, or by pinning them at numerous points between each of the riffles or at a sufficient number of points so as to hold the wires in their proper relation to the table. In place of wires, wire fabric of suitable form and spacing may be used proving it is of such a form as not to disturb unduly the solid particles of the pulp being agitated on the table. The wires need not be directly secured to the table, but may even be independent thereof, but they should be held in such relation to the table as to give them the desired function.

80 Referring to Figure 3, 11 represents generally a table of the Wilfley type having a deck 12 equipped with a set of primary riffles 6 extending generally lengthwise and ending along a diagonal line 6a. Head motion is imparted through a suitable driving mechanism indicated generally at 13. The ore pulp is introduced through a feed box 14 at the upper right hand corner adjacent the head motion. A perforated pipe 15 for supplying dressing water is shown as disposed along the upper 85 side of the table. Launders 16 and 17 are provided at one end and along the lower side of the table to receive the tails and concentrates. A portion of the launder 17 is shown divided off by the partition 18 to receive that portion of the 90 products of the table ordinarily classed as middlings.

95 As indicated in the drawings, the table is inclined laterally toward the side 19 as well as lengthwise. The lengthwise inclination is usually produced by raising the upper left hand corner 20 of the table, as viewed in Figure 3, so that there will be a downward inclination from this point toward the point of feed. The lower left hand corner 21 may likewise be raised relative to the lower right hand corner 22, or, if desired, on the same level or lower than the corner 22. Tables of this type are generally provided 100 with means, not shown, for varying the inclination of the table laterally and lengthwise according to the operating requirements, and it will be understood that in operation the inclination of the table will be varied as desired.

105 The following are examples of practice, carrying out this invention in the treatment of phosphate ores, on a James Gravity Concentrating Table:

110 Carload lots of phosphate were secured from the Phosphate Mining Company, near Mulberry, Florida. A typical screen test shows the following 115 segregations:

	Per cent
On 8 mesh	2.8
On 10 mesh	15.4
On 14 mesh	35.8
On 28 mesh	39.0
Thru 28 mesh	7.0
	140
	100.0

115 The phosphate was agglomerated into floccules in the manner described in my Patent No. 1,797,- 145 356, and fed to a James standard commercial concentrating table with the proper amount of water to form a freely flowing pulp. The table was run as a blank, without cross wires, as given in Test A below:

TEST A

Blank table. Feed was at the rate of 30 tons per 24 hours

	Assay	
	% B. P. L.	% SiO ₂
10 Heads.....	56.81	21.68
Concentrates.....	68.28	7.49
Tailings.....	11.03	84.46
Indicated B. P. L. recovery.....	96.1%	

TEST B

15 Table fitted with cross wires 1, at right angles to the riffles, spaced 1 1/4 inches apart. Table feed was at rate of 78 tons per 24 hours

	Assay	
	% B. P. L.	% SiO ₂
20 Heads.....	59.10	24.43
Concentrates.....	73.44	5.76
Tailings.....	5.71	90.94
Indicated B. P. L. recovery.....	95.0%	

TEST C

30 Table fitted with cross wires 2, spaced 1 1/4 inches apart, at 45 degrees angle to the riffles. Table feed was at the rate of 126 tons per 24 hours

	Assay	
	% B. P. L.	% SiO ₂
35 Heads.....	59.85	25.59
Concentrates.....	75.40	4.68
Tailings.....	7.01	90.40
Indicated B. P. L. recovery.....	97.3%	

TEST D

45 Table fitted with cross wires 3, spaced 1 1/4 inches apart, beginning at the lower left end of the table, away from the head motion, and extending upwards and across the riffles, at a 22.5 degree angle to the riffles, to the head motion end. Table feed was at the rate of 149 tons per 24 hours

	Assay	
	% B. P. L.	% SiO ₂
55 Heads.....	59.39	26.88
Concentrates.....	73.66	6.38
Tailings.....	7.01	90.84
Indicated B. P. L. recovery.....	97.4%	

TEST E

60 Table fitted with cross wires 2 and 3 (Fig. 2) spaced 1 1/4 inches apart. The table was fed at the rate of 151 tons per 24 hours

	Assay	
	% B. P. L.	% SiO ₂
70 Heads.....	59.85	25.59
Concentrates.....	74.16	7.43
Tailings.....	5.00	92.84
Indicated B. P. L. recovery.....	98.2%	

75 Although I have described my invention set-

ting forth several embodiments thereof, and showing its use in connection with the recovery of phosphate ores, it is to be understood that my invention is not limited thereto. For example, the wires may run in different directions than indicated in the drawings, and may be spaced varying distances apart and may cover varying portions of the table. The wires need not be strictly parallel, and two and even more sets of wires running in different directions may be used. The minerals which may be concentrated by my apparatus are of many characters too numerous to mention here and they comprise practically all of the minerals which are subject to gravity concentration.

I have given figures showing the increase in recovery by the use of my invention, but such figures are not to limit my invention, for example, in Test E, I have obtained a recovery as stated of 151 tons, but in further tests I have been able to feed the table at the rate of 188 tons per 24 hours.

The arrangements of wires which I have described are not necessarily the best for all purposes, but the ideas which I have set forth may be adapted in various forms to various concentrating tables and many ores, so that it may be found that other arrangements than I have specifically described may be more effective under special circumstances. All such variations constitute a part of my invention which is not to be limited, except by the claims appended hereto.

It will further be understood that in lieu of wires, other wire-like members or strips, constituting riffle elements, may be employed provided they are of such form and so spaced with respect to the primary riffles as to perform the essential functions of the cross wires in a similar way.

What I claim is:

1. An apparatus for ore concentration which comprises a table, riffles in the surface thereof, means for imparting motion to said table, and means on said table for increasing the mobility of ore being treated, said means including two sets of substantially parallel wires at an angle to said riffles, one set being at the heads end of said table and the other set being adjacent thereto, the two sets being at right angles to each other.

2. An apparatus for concentrating ore by wet gravity methods including a normally laterally inclined separating table, riffles extending lengthwise of the surface thereof, means for imparting vibratory motion to said table in a direction substantially parallel to that of said riffles, means for feeding dressing water to said table adjacent the upper edge thereof, and means superimposed on said riffles for increasing the mobility of the ore being treated, for retarding the movement of the lighter constituents of the ore lengthwise of said table while permitting the heavier constituents to pass freely along paths defined by said riffles, and for guiding said lighter constituents off the table in paths transverse to those defined for the heavier constituents by said riffles, said means being further so positioned with respect to said riffles as to be disposed in the body of material being fed across said table.

3. An apparatus for concentrating ore by wet gravity methods including a normally laterally inclined separating table, riffles extending lengthwise of the surface thereof, means for imparting vibratory motion to said table in a direction substantially parallel to that of said riffles,

means for feeding dressing water to said table, and means superimposed upon and extending across said riffles and extending over a substantial portion of the area of said table adjacent 5 to the heads end for increasing the mobility of the ore being treated, for retarding the movement of the lighter constituents of the ore lengthwise of said table while permitting the heavier constituents to pass freely along paths defined by 10 said lengthwise riffles, and for guiding said lighter constituents off the table in paths transverse to those defined for the heavier constituents by said riffles, said means being further so positioned with respect to said riffles as to be disposed in 15 the body of material being fed across said table.

4. An apparatus for concentrating ore by wet gravity methods including a normally laterally inclined separating table, riffles extending lengthwise of the surface thereof, means for imparting vibratory motion to said table in a direction substantially parallel to that of said riffles, means for feeding dressing water to said table adjacent the upper lateral edge thereof, and means on said table for increasing the mobility 20 of the ore being treated, for retarding the movement of the lighter constituents of the ore lengthwise of said table while permitting the heavier constituents to pass freely along paths defined by said lengthwise riffles, said means including a series of substantially parallel wires superimposed upon said riffles at an angle thereto and extending generally transversely of the mean or average 25 direction of material across the table from a point adjacent the point of feed of material to said table over at least a substantial portion of said table, said wires being further so positioned as to move in the material being fed across the 30 table.

3. An apparatus for concentrating ore by wet gravity methods including a substantially rectangular, normally laterally inclined table, riffles extending lengthwise of the surface thereof, means for imparting vibratory motion to said table in a direction substantially parallel to that of said riffles, whereby the heavier constituents of an ore pulp introduced adjacent one end of the table will be moved along said table to the 35 opposite end thereof and the lighter constituents of said ore pulp will be moved laterally of said table, means for feeding dressing water to said table adjacent the upper edge thereof, and means for increasing the mobility of the ore being treated and to accelerate the movement of the lighter constituents of the ore laterally across the table, said means comprising a series of cross riffles superimposed upon and extending across said 40 lengthwise riffles toward the lateral discharge side of the table, said series of riffles covering at least a substantial portion of the table adjacent the heads end thereof and being so positioned as to be disposed within the material being fed across the table.

5. An apparatus for concentrating ore by wet gravity methods including a table of the type adapted to be reciprocated to feed the ore across 45 the surface thereof, said table including a plurality of substantially parallel riffles arranged substantially parallel with respect to the direction of reciprocation, means for feeding dressing water to said table, and a plurality of substantially parallel wire-like members overlying an extended area of the riffles adjacent the point of feed of ore pulp to said table and positioned in the material on the table at a substantial angle with respect to said riffles, the table being inclined in a direction generally transverse the 50 riffles, whereby, in operation, the concentrate and the tailings are discharged from the table in different directions with respect to the extension of the riffles, the angularity of the said wire-like members being such that they extend generally transversely to the general or mean direction of movement of the ore from the point of application thereof to the table.

6. An apparatus for concentrating ore by wet gravity methods including a table of the type adapted to be reciprocated to feed the ore across the surface thereof, said table including a plurality of substantially parallel riffles arranged substantially parallel with respect to the direction of reciprocation, means for feeding dressing water to said table, and a plurality of substantially parallel wire-like members overlying an extended area of the riffles adjacent the heads end of said table and positioned in the material on the table at a substantial angle with respect to said riffles, the table being inclined in the direction in which the riffles extend and further being inclined generally transversely of said riffles, whereby, in operation, the concentrate 60 is discharged from the table at one edge there-

of and the tailings are discharged at another edge, the angularity of the said wire-like members being such that they extend approximately parallel to the general or mean direction of movement of the ore from the point of application thereof to the table. 80

7. An apparatus for ore concentration which comprises a table, riffles extending lengthwise of the surface thereof, means for imparting vibratory motion to said table in a direction substantially parallel to that of said riffles, and means on said table for increasing the mobility of ore being treated and for retarding the movement of the lighter constituents of the ore lengthwise of said table while permitting the heavier constituents to pass freely along paths defined by said lengthwise riffles, said means including a series of substantially parallel wires superimposed upon said riffles at an angle thereto and extending generally transversely of the mean or average 90 direction of material across the table from a point adjacent the point of feed of material to said table over at least a substantial portion of said table, said wires being further so positioned as to move in the material being fed across the 100 table.

8. An apparatus for concentrating ores by wet gravity methods including a substantially rectangular, normally laterally inclined table, riffles extending lengthwise of the surface thereof, means for imparting vibratory motion to said table in a direction substantially parallel to that of said riffles, whereby the heavier constituents of an ore pulp introduced adjacent one end of the table will be moved along said table to the 105 opposite end thereof and the lighter constituents of said ore pulp will be moved laterally of said table, means for feeding dressing water to said table adjacent the upper edge thereof, and means for increasing the mobility of the ore being treated and to accelerate the movement of the lighter constituents of the ore laterally across the table, said means comprising a series of cross riffles superimposed upon and extending across said lengthwise riffles toward the lateral discharge side 110 of the table, said series of riffles covering at least a substantial portion of the table adjacent the heads end thereof and being so positioned as to be disposed within the material being fed across the table. 115

9. Ore concentrating apparatus including a normally laterally inclined separating table having a plurality of substantially parallel riffle elements on the surface thereof and being of a type adapted to feed ore thereacross under the influence of vibratory or reciprocatory motion of the table and of dressing water flowing over the surface of the table, and to discharge separated materials in different directions with respect to the extension of said riffle elements, means for feeding ore and dressing water to said table adjacent the upper side thereof, means for increasing the mobility of the ore being treated, for retarding the movement of the lighter constituents of the ore in the general direction of reciprocation of the table while permitting the heavier constituents to pass freely along paths defined by said 125 riffles, and for guiding said lighter constituents off the table in paths transverse to those defined for the heavier constituents by said riffles, said means comprising a plurality of additional riffle elements superimposed upon said first-mentioned riffle elements and disposed in the path of movement of the material across the table, and further extending generally transversely of the general 130

140

145

150

direction of extension of said first-mentioned riffle elements from a point adjacent the point of feed of material to said table over at least a substantial portion of said table.

5 10. Ore concentrating apparatus including a normally laterally inclined separating table of a type adapted to feed ore thereacross under the influence of vibratory or reciprocatory motion imparted to said table and of dressing water flowing over the surface of the table, and to discharge separated materials in different directions with respect to the extension of riffle elements arranged on the surface thereof, said riffle elements being further arranged substantially parallel to one another and to the direction of reciprocation of the table, means for feeding dressing water to said table adjacent the upper edge thereof, and a plurality of additional riffle elements superimposed upon the first-mentioned riffle elements and disposed in the path of movement of the material across the table, and extending over at least a substantial portion of the area of the table and generally transversely of the mean or average direction of movement of material across the table.

25 11. Ore concentrating apparatus including a normally laterally inclined separating table of a type adapted to feed ore thereacross under the influence of vibratory or reciprocatory motion imparted to said table and of dressing water flowing over the surface of the table, and to discharge separated material in different directions with respect to the extension of riffle elements arranged on the surface thereof, said riffle elements being further arranged substantially parallel to one another and to the direction of reciprocation of the table, means for feeding dressing water to said table adjacent the upper edge thereof, and a plurality of additional riffle elements superimposed upon the first-mentioned riffle elements and disposed in the path of movement of the material across the table, and extending over at least a substantial portion of the area of the table and in a direction generally paralleling the mean or average direction of movement across the table.

45 12. Ore concentrating apparatus including a normally laterally inclined separating table of a type adapted to feed ore thereacross under the influence of vibratory or reciprocatory motion imparted to said table and of dressing water flowing over the surface of the table, and to discharge separated materials in different directions with respect to the extension of riffle elements arranged on the surface thereof, said riffle elements being further arranged substantially parallel to one another and to the direction of reciprocation of the table, means for feeding dressing water to said table adjacent the upper edge thereof, and a plurality of additional riffle elements superimposed upon the first-mentioned riffle elements and disposed in the path of movement of the material across the table, and extending over at least a substantial portion of the area of the table and at an angle of approximately 22.5° with respect to the riffle elements first mentioned.

65 13. An ore concentrating table of the type adapted to be reciprocated to feed the ore across the surface thereof, said table including a plurality of substantially parallel riffles arranged substantially parallel with respect to the direction of reciprocation, a set of substantially parallel wire-like members overlying an extended area of the riffles and positioned in the material on the table at a substantial angle with respect to

said riffles, and an additional set of substantially parallel wire-like members overlying another extended area of the riffles and positioned in the material on the table at a substantial angle with respect to said riffles, the table being inclined in the direction in which the riffles extend and further being inclined generally transversely of said riffles, whereby, in operation, the concentrate and the tailings are discharged from the table in different directions with respect to the extension of the riffles, the angularity of the two sets of wire-like members being such that the members in one set extend approximately perpendicularly to the general or mean direction of movement of the ore from the point of application thereof to the table and the members of the other set extend approximately parallel to the general or mean direction of movement of the ore from the point of application thereof to the table.

80 14. An apparatus for ore concentration including a table, riffles extending lengthwise of the surface thereof, means for imparting vibratory motion to said table in a direction substantially parallel to that of said riffles, means superimposed upon and extending across said riffles and extending over a substantial portion of the area of said table adjacent the heads end for increasing the mobility of the ore being treated and for retarding the movement of the lighter constituents of the ore lengthwise of said table while permitting the heavier constituents to pass freely along paths defined by said lengthwise riffles, and additional means superimposed upon and extending across said riffles and extending over a substantial portion of the area of said table from a point adjacent said first-mentioned means, said means being adapted to retard the movement of the lighter constituents of the ore lengthwise of said table while accelerating the lateral movement thereof.

95 15. An apparatus for ore concentration which comprises a substantially rectangular, normally laterally inclined table, riffles extending lengthwise of the surface thereof, means for imparting vibratory motion to said table in a direction substantially parallel to that of said riffles, whereby the heavier constituents of an ore pulp introduced adjacent one end of the table will be moved along said table to the opposite end thereof and the lighter constituents of said ore pulp will be moved laterally of said table, and means for increasing the mobility of the ore particles adjacent the feed end of the table while retarding the longitudinal movement of the lighter constituents of the ore, said means comprising a series of cross riffles superimposed upon and extending across said lengthwise riffles over a substantial portion of the area of said table adjacent the heads end thereof, and means for accelerating the movement of the lighter constituents of said ore laterally across the table and discharge thereof at a side of said table, said means comprising a series of cross riffles superimposed upon and extending across said lengthwise riffles that are disposed on a substantial portion of the area of said table adjacent the first-mentioned set of cross riffles but more remote from the heads end of said table, said second set of cross riffles being disposed at a substantial angle to the cross riffles comprising said first-mentioned set of cross riffles.

100 16. Ore concentrating apparatus including a separating table having a plurality of substantially parallel riffle elements on the surface thereof and being of a type adapted to feed ore there-

80

- across under the influence of vibratory or reciprocatory motion of the table and to discharge separated materials in different directions with respect to the extension of said riffle elements, a plurality of riffle elements disposed in the path of movement of the material across the table and extended in a direction generally transverse the mean or average direction of movement of the material, and a plurality of additional riffle elements also disposed in the path of movement of the material across the table and extended in a direction generally paralleling the mean or average direction of movement of the material across the table. 80
15. 17. Ore concentrating apparatus including a separating table having a plurality of substantially parallel riffle elements on the surface thereof and being of a type adapted to feed ore thereacross under the influence of vibratory or reciprocatory motion of the table and to discharge separated materials in different directions with respect to the extension of said riffle elements, a plurality of riffle elements disposed in the path of movement of the material across the table and extended in a direction generally transverse the mean or average direction of movement of the material, a plurality of additional riffle elements also disposed in the path of movement of the material across the table and extended in a direction generally paralleling the mean or average direction of movement of the material across the table, the riffle elements second mentioned being disposed in advance of the riffle elements last mentioned with respect to the direction of movement of the material across the table. 90
18. An apparatus for ore concentration which 95
- comprises a substantially rectangular, normally laterally inclined table, riffles extending lengthwise of the surface thereof, means for imparting vibratory motion to said table in a direction substantially parallel to that of said riffles, a series of cross riffles superimposed upon and extending across said lengthwise riffles over a substantial portion of the area of said table adjacent the heads end thereof, said cross riffles being so disposed with respect to the lengthwise riffles as to retard longitudinal movement of the lighter constituents of the ore while permitting the heavier constituents to pass therebeneath along the paths defined by the lengthwise riffles, and a second series of cross riffles disposed at an angle to the first-mentioned cross riffles and extending diagonally across the lengthwise riffles from points adjacent said first-mentioned cross riffles toward the lower side of said table. 100
19. An apparatus for ore concentration which 105
- comprises a table, riffles, extending lengthwise of the surface thereof, means for imparting vibratory motion to said table in a direction substantially parallel to that of said riffles, and means on said table for increasing the mobility 110 of the ore being treated, for retarding the movement of the lighter constituents lengthwise of said table and for accelerating their movement laterally thereof, all while permitting the heavier constituents to pass freely along paths defined by said lengthwise riffles, said means including two sets of substantially parallel wires, said sets being disposed at an angle to said riffles and to each other, one set being at the heads end of said table and the other set being adjacent thereto. 115
